Primary Examiner — Angela J Lee(74) *Attorney, Agent, or Firm* — Wagenknecht IP Law Group PC(57) **CLAIM**

The ornamental design for a dual stand for electronic devices, as shown and described.

DESCRIPTION

FIG. 1 is a front, top, and left side perspective view of a dual stand for electronic devices showing our new design;

FIG. 2 is a rear, top and right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a front, top and left perspective view thereof, shown holding two electronic devices.

The broken lines are for illustrative purposes only and form no part of the claimed design.

1 Claim, 9 Drawing Sheets(56)
